UNITED STATES PATENT OFFICE

STEPHEN W. BOURN, OF BRISTOL, RHODE ISLAND, ASSIGNOR TO UNITED SHOE MACHINERY CORPORATION, OF PATERSON, NEW JERSEY, A CORPORATION OF NEW JERSEY

SHOE SURFACE COATING

Application filed July 5, 1924. Serial No. 724,342.

This invention relates to coating boots and shoes and is herein disclosed in a machine for and a novel method of applying a fluid such as cement to the foxing areas and bottoms of shoes.

During the manufacture of a canvas tennis shoe and preparatory to the attachment of the rubber sole, a strip of gum rubber is applied to the lower margin of the periphery of the shoe to which the edge of the sole is later vulcanized. In order to secure this strip of gum rubber, known as the "foxing", to the canvas top or upper of the tennis shoe, a stripe of cement is applied to the lowermost margin of the sides of the shoe adjacent to the bottom of the shoe in the section known as the foxing area. Although various machines have been suggested for this operation of foxing cementing, prior to my invention it has been usually performed by hand. For high grade work, however, a stripe of uniform width must be applied so that in the finished shoe the cement will come exactly to the upper edge of the foxing strip in order to secure it firmly to the shoe, and will not project above this strip. If it so happens that the stripe of cement is too wide, it will show above the foxing strip in the completed shoe thereby producing a blemish which can only be removed with difficulty and which usually results in making the shoe a "second".

Having this in mind, an object of the invention is to render it easier for the operator to apply a coating to the foxing area of a shoe quickly and accurately so that the line of demarcation between the foxing area and the uncoated portion of the upper of the shoe is sharply defined and exactly located. To this end I have provided a novel method of coating the foxing area of a shoe in accordance with which the upper of the shoe above the foxing area is shielded from the application of cement and the upper edge of the stripe of cement is properly positioned. As herein exemplified, a shoe and an apertured shielding member arranged to surround the shoe are brought into cooperative relation, with the margin of the opening closely related to the shoe and arranged exactly at the upper edge of the foxing area and cement is applied

to the exposed foxing area. Excessive care or skill in applying the cement is not required and the whole foxing area may be quickly and accurately coated.

Another object of the invention is to provide an improved machine for coating the foxing areas of shoes by means of which the time required for the operation may be decreased and the cost reduced without sacrificing any of the accuracy required for the production of high class work.

A feature of the invention in its machine aspect consists in providing a shielding member having an aperture shaped like a shoe and constructed and arranged to surround the shoe with the edge of the aperture located at the upper edge of the foxing area. As herein illustrated the edge of the apertured shielding member is curved heightwise of the shoe so that it coincides with the upper edge of the foxing area and exposes an area of substantially uniform width.

Still another feature of the invention includes means for turning a shoe to present portions of the foxing area successively to a cement-applying device which is movably mounted, thereby at least in part to compensate for the irregular outline of the shoe, and having, interposed between the applying device and the shoe, shielding means constructed and arranged to coact with the shoe at the upper edge of the foxing area whereby the stripe of cement applied to the shoe will be substantially uniform in width and have its upper edge at a uniform distance from the bottom of the shoe.

In accordance with features of the invention, the illustrated machine is arranged to rotate the shoe about a fixed axis and a fluid applying device is mounted for reciprocation toward and away from the axis of rotation, means being provided to cause the applying device to follow the outline of the work as it is rotated. As illustrated, the construction and arrangement are such that gravity tends to hold the applying device in contact with the work, a counter-balancing spring being provided to facilitate the movements of the latter, and a cam rotating in timed relation to the shoe support moves the fluid applying

device positively to and fro to keep it in the desired relation to the margin of the rotating work.

- Present shoe factory practice usually requires the application of a series of coatings so that, in spite of the porosity of the work, a sufficient quantity of the adhesive will remain upon the surface of the work securely to bind the foxing strip to the canvas of the upper.
- 10 In order, therefore, that the illustrated machine may be operated to apply more than one coating to the shoe and in accordance with features of the invention, means are provided for rotating the shoe a predetermined number of revolutions and for then stopping the machine. Still other means are provided for automatically shutting off the supply fluid when the work has been rotated a given number of revolutions.
- 20 These and other features of the invention are set forth in the following specification and illustrated in the accompanying drawings, in which,—

Figure 1 is a sectional side elevation of my improved machine illustrating means for rotating the work and the means for applying liquid thereto.

Figure 2 is a front view showing a portion of a machine with the work mounted on the 30 rotatable plate and showing the liquid-applying means as mounted to reciprocate during the supplying action.

Figure 3 is a horizontal section through the top of the machine looking down upon the 35 stop mechanism.

Figure 4 is a detail view in elevation of the stop mechanism.

Figure 5 is a detail view showing the gears through which the stop mechanism is actuated.

Figure 6 is a side elevation illustrating a fragment of the main drive.

My novel method of applying cement to the foxing areas of shoes may be carried out 45 advantageously by means of the illustrated apparatus in which the upper of the shoe above the foxing area is shielded, means being provided for rotating the work about a relatively fixed axis and cooperating means 50 provided for moving the fluid-applying device towards and from the axial center about which the work rotates for the purpose of applying the fluid to the desired portion of the work, which may be the foxing portion, 55 or the adjacent margin of the bottom of the shoe, or any other similar portion thereof.

With reference to the drawings, the machine has a frame 10 in which is mounted a rotatable face plate 11 on which the work 60 such as a lasted tennis shoe 12 is mounted. This face plate is itself mounted on a shaft 13 which is journaled on the frame 10 and is rotated from a drive pulley 14 (Fig. 6) by means of meshing gears 15, 16, the latter of 65 which is loosely mounted on a vertical shaft

17. A sliding clutch member 18 is splined on this shaft 17 to cooperate with a clutch member on the gear 16. By a connection through mitre gears 19, fixed respectively to shafts 17 and 13, the face plate 11 is rotated and in turn rotates the work about the axis of the shaft 13.

The rear surface of this face plate is grooved to form a cam path 20 corresponding to the outline of the shoe 12 to be treated.

70 In order to support a liquid-applying device such as a brush 21 which is herein shown as applying liquid to the foxing portion 22 of the shoe, or a brush 23 which is herein shown as adapted to apply liquid to the bottom of the shoe, I have mounted a vertically-disposed slide plate 24 to slide in ways provided by guides 25 on the main, upright frame, which plate is provided with a bracket 26 in which a tube 27 is rigidly mounted to support the brushes 21 and 23. These brushes are supplied with liquid from a supply tank 28 through a flexible tube 29 joined to the tube 27.

75 This slide plate 24 is provided with a roller 30 which engages the groove 20 in the face plate 11, whereby the rotation of this face plate causes the slide plate 24 to reciprocate towards and from the axis on which the work rotates.

80 A portion of the weight of the slide plate and the tube is supported by a spring 31 which is coiled about a guide rod 32, the upper end of the spring engaging a boss 33 on the slide plate, while the lower end engages a boss 34 on the frame, the guide rod 32 extending through this latter boss.

85 A blower 34' is provided to generate air pressure in the liquid supply tank for the purpose of forcing and feeding this liquid to the applying brushes. This blower 34' being arranged to force air up through pipe 35 into the chamber above the liquid.

90 Inasmuch as it may be desired to apply one or more successive coatings to the peripheral margin of the shoe, it is found convenient to arrange the mechanism so that the shoe may be rotated for any desired number of turns and then stopped without requiring the operator to keep track of the number of revolutions made. To this end automatic mechanism is provided for regulating the number of turns that the work shall make during application of the liquid thereto and for then 100 causing the machine to stop. I have, accordingly, connected an operating handle 36 to the clutch 18 and to this operating handle is connected a trip rod 37 which extends up through the frame table 38. The rod 37 is provided with a latch lip 39, see Figure 4, which engages the upper edge of the table thereby serving to hold the clutch in engagement, and in order to throw this latch 39 out of engagement with the table, I have provided an arm 40 mounted on a short shaft 41, 105

which shaft is rotated from the shaft 17 through mitre gears 42, short shaft 43, pinion gear 44, idler gear 45, (Fig. 5), large gear 46, shaft 47 and mitre gears 48. The ratio of these gears 44 and 46 determines the number of revolutions that the work 12 will make before the machine is stopped, which ratio may be varied by changing the ratio of the gears 44 and 46 and then adjusting the idler gear 45 in its lever 49 to transmit motion through the ratio gears.

In view of the character of the machine and the necessity for cleanliness in order to produce the best work, the machine is provided with automatic mechanism for stopping the flow of fluid at the end of each operation in timed relation to the stopping of the shoe. The time for shutting off the fluid may or may not coincide with the stopping of the shoe. Consequently in order to arrest the flow of the fluid from the tank 28 to the brushes 21 and 23, I have mounted a valve 50 on the tube 51 and on this valve I have mounted an arm 52 which engages a cam plate 53 on the shaft 41 so that as said shaft rotates, a notch 54 in the plate 53 is presented beneath the valve lever 52 which permits this lever to drop under tension of spring 55 to close the valve and shut off the supply of fluid to the brush.

In some instances it is found of advantage to be able to stop the feed of the liquid after a single application thereof to the work and at the same time to permit the work to continue its rotation to facilitate drying one coat of the liquid before another is applied. To accomplish this result in a simple way, I have hinged at 60 the outer end of arm 40 whereby it may be tipped up by the operator and swung back upon itself so that when rotated it will not engage and knock off the latch 39 to stop the machine, only accomplishing this result when swung down into extended position by the operator, as shown in the drawings.

Having now described the general arrangement of the machine it remains to describe that improved feature of my invention by means of which the portion of the upper lying above the foxing area is protected and the line of demarcation between the stripe of cement and the uncoated portion of the shoe upper is accurately controlled. In the arrangement herein illustrated a portion of the lasted shoe which is not to be coated is protected by means of an apertured shield 56 entirely surrounding the shoe and having the edges of its opening brought into close relation to the shoe at the upper edge of the foxing area. The edge of the opening in the shield 56 is, as will be seen from the drawings, curved heightwise of the shoe so as to coincide accurately with the upper edge of the foxing area to expose an area of substantially uniform width.

This guard or shield 56 may be supported in any suitable way, the guard herein illustrated being provided with a flange 57 secured to the face plate 11 and extending down to the upper edge of the foxing portion. Since the shield and the shoe are both mounted upon the same supporting plate 11, their relative position is accurately determined for any size and style of shoe and it is only necessary for the operator to move a shoe through the apertured shielding member to bring it into cooperative engagement with the supporting plate 11 in order to be sure that the predetermined portion at the lower part of the shoe is exposed beyond the edge of the shielding device. It will be understood that a succession of shoes of the same size and shape may be mounted upon the machine, one after another, and positioned within the guard. Because of the shape of the guard and of the shoe, it will not be necessary to remove the guard each time the shoe is changed, but only when the size or type of shoe to be inserted is considerably different from those previously treated.

In practising my novel method by the aid of the illustrated machine, the operator will take a lasted shoe 12 of a size for which the machine is fitted at the moment, and pass it through the opening of the shielding device 56 and mount it upon the rotatable work supporting plate 11. By reason of the design of the machine, this will locate the shoe exactly with respect to the shielding member and the operator will proceed to start the machine by manipulation of the hand lever 36. A protected shoe will then be rotated past the cement applying device which will coat both the foxing area and the bottom of the shoe, said applying device being moved to and fro to cause it to rest in easy engagement with the peripheral portion of the shoe. After the shoe has made the desired number of revolutions, the automatic mechanism heretofore described will shut off the cement and stop the rotation of the shoe support either synchronously or at the desired interval.

My improved device for applying liquid to shoes and other articles, is very simple and practical in construction and effective in its operation and by its use liquid may be applied to work having irregular outlines.

I claim:

1. In a shoe surface coating machine, means for rotatably supporting a shoe, means for rotating said supporting means, a spreader for applying fluid to the shoe, and means for reciprocating said spreader towards and from the axis of rotation of the shoe as the latter rotates to keep the spreader in contact with the shoe.
2. In a shoe surface coating machine, means for supporting a shoe for rotation

- about an axis, a fluid spreader mounted for to-and-fro movement, and means including a pattern plate constructed and arranged to move said spreader to follow the outline of the shoe as it rotates.
3. In a shoe surface coating machine, means for rotating a shoe about a relatively fixed axis, a fluid spreader, and means for moving said spreader to cause it to move in and out in accordance with the shape of a shoe so as to follow the outline of the shoe as it rotates.
4. In a shoe surface coating machine, means for rotating a shoe about a relatively fixed axis, a movably mounted fluid spreader, and cam means for controlling the movement of said spreader in timed relation to movement of the shoe so that the spreader will follow the outline of the shoe as rotated.
5. In a shoe surface coating machine, means for rotating a shoe, a fluid spreader, means for causing said spreader to move and follow the outline of the shoe as it rotates, and a guard member rotating with said shoe for restricting the effective action of the spreader.
6. In a shoe surface coating machine, means for rotating a shoe, a fluid applying device slidably supported above the shoe and resting on the shoe, and a cam for reciprocating said device to and fro to cause it to follow the outline of the shoe as the latter is rotated.
7. In a shoe surface coating machine, means for rotating a shoe, a fluid applying device, slidably mounted above the shoe, resilient means tending to balance the weight of said device, and a cam for positively moving said device to and fro to cause it to move towards and from the axis of rotation of the shoe and to follow the outline of the shoe while applying the fluid.
8. In a shoe surface coating machine, means for rotating a shoe, a fluid applying device having a shut-off, a cam for moving said applying device towards and from the axis of rotation of the shoe to follow the outline of the shoe while applying the fluid, and stop mechanism responsive to the rotation of the shoe constructed and arranged to act upon the shoe rotating means and the fluid shut-off thereby to arrest the action of the machine and the flow of the fluid after a predetermined number of revolutions of the shoe.
9. In a shoe surface coating machine, a work supporting plate, means for rotating said plate and work, a cam groove in said plate following the general outline of the shoe to be treated, and a slide plate carrying fluid-applying means and caused to reciprocate by engagement with said cam groove to cause the applying means to follow the outline of the shoe.
10. In a shoe surface coating machine, a work supporting plate, means for rotating
- said plate and work, a cam groove in said plate following the general outline of the shoe to be treated, a slide plate carrying fluid applying means and caused to reciprocate by engagement with said cam groove to cause the applying means to follow the outline of the shoe, a supply tank, and a flexible tube connecting said tank through which fluid is supplied to said applying means.
11. In a shoe surface coating machine, means for rotating a shoe, a movably mounted spreader member positioned to apply liquid to the bottom of the shoe, means for moving said spreader member to and from the axis of the shoe including a cam constructed and arranged to control the movement of the said means to cause the spreader member to follow the outline of the shoe.
12. In a shoe surface coating machine, means for rotating a shoe, a spreader member for applying liquid to the surface of the shoe, and a guard member rotating with said shoe and protecting that portion of the surface not to be treated.
13. In a shoe surface coating machine, a frame, a work support, a fluid spreader, means for moving both the work and the spreader relatively to the frame and to each other in applying the fluid to the work, and stopping mechanism for arresting the flow of the fluid to the spreader after a predetermined number of revolutions of the work.
14. The method of coating the foxing area of a shoe which consists in relatively positioning a shoe and a shielding device in a close relation to cover up the whole upper part of the shoe so that only a predetermined annular portion of the lower part of the shoe, known as the foxing area, is exposed, holding this relation constant and applying cement to at least the greater portion of the exposed foxing area.
15. The method of coating the foxing area of a shoe which consists in moving a shoe into position with respect to a shielding device surrounding the shoe thereby to expose the foxing area while protecting all of that part of the shoe upper above the foxing area from the application of cement, and applying cement to at least the greater portion of the exposed foxing area.
16. The method of applying cement to the foxing area of a shoe which consists in moving the shoe through an apertured shielding member to expose the foxing area while protecting the part of the shoe upper above the foxing area from the application of cement, and causing a relative movement of translation between the shielded shoe and the cement applying means while applying cement to at least the greater portion of the exposed foxing area.
17. That method of applying cement to the foxing area of a shoe, the upper portion of

which is surrounded by a shield to prevent the application of cement thereto, which is characterized by causing a relative movement of translation between an applying device and the shielded shoe to present successive portions of at least the greater portion of the foxing area to the applying device.

18. That method of applying cement to the foxing area of a shoe, the whole upper portion of which is shielded to prevent the application of cement thereto which is characterized by causing a relative movement of translation between an applying device and the shielded shoe to coat the whole vertical extent of each successive portion of the foxing area at any part of the shoe which is brought into cooperative relation with the applying device, and moving the shielding means with the shoe to maintain substantially constant the relation between the two.

19. That method of applying cement to the foxing area of a shoe which consists in applying to the shoe a shielding device to surround and protect the portion of the upper lying above the foxing area, positioning said shielded shoe in operative relation to a cement applying device and causing relative movement of the shoe with its shielding device and the applying device to coat the whole of the unshielded foxing area.

20. In a foxing-cementer, cement applying means, and a shield having a shoe-receiving opening corresponding in shape substantially to the peripheral outline of the bottom of a shoe and constructed and arranged to protect the upper of a shoe above the foxing area from the application of cement while exposing the foxing area of the shoe to the action of the cement applying means.

40 21. In a foxing-cementer, means for applying a stripe of cement to the foxing area of a shoe, and means for controlling the line of demarcation between the stripe of cement and the portion of the shoe upper above the foxing area, said last-named means comprising a shield having an opening corresponding in outline substantially to the peripheral outline of the bottom of the shoe.

50 22. In a foxing-cementer, means for applying a stripe of cement to the foxing area of a shoe, a shield having a shoe-receiving opening corresponding in outline to the shape of the bottom of the shoe, and means for determining the position of a shoe relatively to the opening in said shield to locate portions of the upper of the shoe respectively on opposite sides of the shield, said positioning means and said shield being constructed and arranged to determine the position upon the shoe of the upper edge of the stripe of cement and to protect the portion of the upper above the foxing area from the application of cement.

60 23. In a foxing-cementer, a shield having

an opening corresponding in shape substantially to the peripheral outline of the bottom of a shoe and arranged to be located in juxtaposition to the upper of a shoe to define the upper edge of the foxing area of the shoe, 70 the part of the shield bounding the opening being curved heightwise of the shoe thereby to expose a foxing area of substantially uniform width, and means for applying a stripe of cement to said foxing area as determined by 75 said shield.

24. In a foxing-cementer, a shield having an opening corresponding in shape substantially to the peripheral outline of the bottom of a shoe and constructed and arranged to be brought into juxtaposition to the upper of a shoe, upon relative positioning movement of the shield and the shoe, to define the upper edge of the foxing area of the shoe, said shield being curved heightwise of the shoe 80 thereby to expose a foxing area of substantially uniform width, and means for applying a stripe of cement to said foxing area as so defined.

25. In a foxing cementing machine, a cement applying device, a movable shoe support, shoe-surrounding means carried thereby for shielding the whole upper portion of a shoe to protect said portion from the application of cement, and means for causing a 90 relative movement of translation between said cement applying device and the shoe support and shielding means to present successive portions of the foxing area to the applying device.

26. In a foxing cementing machine, a shoe support, means for applying cement to the foxing area of a shoe on said support, an imperforate shielding member surrounding the shoe to protect that portion of the upper of the shoe which lies above the foxing area, and means for supporting said shielding member in a predetermined relation to the shoe support constructed and arranged to cause the edge of the shielding member to come automatically into the desired relation to the edge of the foxing area as the shoe is applied to the shoe support.

27. In a foxing cementing machine, cement applying means, means for supporting a lasted shoe, means for applying cement to the foxing area of the shoe, and an imperforate shielding member mounted in fixed relation to said shoe support and constructed and arranged to surround the shoe, said shielding member having an edge shaped and arranged to lie immediately adjacent to the upper edge of the foxing area of the shoe when the shoe is positioned upon the shoe support to cause the application of cement to be limited to the foxing area.

28. In a foxing cementing machine, a cement applying device, a movable support for a lasted shoe, means for moving said

- support constructed and arranged to transfer a lasted shoe from one position to another past said applying device in order to effect the coating of the whole of the foxing
- 5 area of the shoe with cement, and an imperforate shielding member mounted on said movable support for movement with the shoe, said shielding member being constructed and arranged to surround the shoe with
- 10 an edge lying immediately adjacent to the upper edge of the foxing area whereby the upper of the shoe above the foxing area is protected from the application of cement.
- 15 29. In a foxing cementing machine, a cement applying device, a member constructed and arranged to support a lasted shoe and movable to present various portions of the foxing area of the shoe to the cement applying device, and an imperforate shielding member mounted upon said movable member and constructed and arranged to protect from cement both the upper of the shoe above the foxing area and the movable member adjacent to said shoe support.
- 20 30. In a foxing cementing machine, a rotatable member constructed and arranged to serve as a support for a lasted shoe, a movably mounted cement applying device, means for rotating said support and simultaneous
- 25 45 moving said applying device to maintain it in cooperative relation with the foxing area of the moving shoe, and an imperforate shielding member mounted on said movable support and constructed and arranged to protect from the application of cement the upper of the shoe above the foxing area thereof with its upper edge portion close to the upper edge of the foxing area, thereby
- 30 to determine the line of demarcation between the cemented and uncemented portions.
- 35 31. In a foxing cementing machine, a movably mounted cement-applying device, means for supporting a lasted shoe for turning movement to present successive portions of the foxing area of the shoe to the applying device, means for holding said device in cement-applying relation to the shoe, and shielding means interposed between said device and the shoe and having an edge in close relation to the upper edge of the foxing area of the shoe thereby to limit the application of cement to portions of the shoe below that edge.
- 40 32. In a foxing cementing machine, a cement-applying device to deposit a stripe of cement around a shoe, a movable support for said device, means for supporting a shoe constructed and arranged to present various portions of the foxing area successively to said applying device, and shielding means, interposed between the applying device and the shoe, for determining the upper limit of the stripe of cement deposited on the shoe,
- 45 said means being constructed and arranged
- to maintain the upper edge of the foxing area at substantially a uniform distance from the bottom of the shoe.
- In testimony whereof I affix my signature.
